FIG. 6 is a detail view taken from FIG. 5;

FIG. 7 is a top plan view thereof;

FIG. 8 is a rear elevational view thereof;

FIG. 9 is a rear elevational view thereof with the strap
removed;

FIG. 10 is a bottom plan view thereof;

FIG. 11 is a right-side elevational view thereof;

FIG. 12 is a left-side elevational view thereof;

FIG. 13 is a detail view taken from FIG. 12;

FIG. 14 is a right-front perspective view of the combined
headset with mask in a second position; the left-front perspec-
tive view being a mirror image;

FIG. 15 is a right-rear perspective view thereof, the left-rear
perspective view being a mirror image;

FIG. 16 is a front elevational view thereof;

FIG. 17 is a top plan view thereof;

FIG. 18 is a rear elevational view thereof;

FIG. 19 is a bottom plan view thereof;

FIG. 20 is a right-side elevational view thereof;

FIG. 21 is a left-side elevational view thereof;

FIG. 22 is a right-front perspective view of the combined
headset with mask in a third position; the left-front perspec-
tive view being a mirror image;

FIG. 23 is a right-rear perspective view thereof, the left-rear
perspective view being a mirror image;

FIG. 24 is a front elevational view thereof;

FIG. 25 is a top plan view thereof;

FIG. 26 is a rear elevational view thereof;

FIG. 27 is a bottom plan view thereof;

FIG. 28 is a right-side elevational view thereof;

FIG. 29 is a left-side elevational view thereof;

FIG. 30 is a right-front perspective view of the combined
headset with mask in a fourth position;

FIG. 31 is a right-rear perspective view thereof;

FIG. 32 is a front elevational view thereof;

(Continued)

FIG. 33 is a top plan view thereof;
FIG. 34 is a rear elevational view thereof;
FIG. 35 is a bottom plan view thereof;
FIG. 36 is a right-side elevational view thereof;
FIG. 37 is a left-side elevational view thereof;
FIG. 38 is a right-front perspective view of the combined headset with mask in a fifth position;
FIG. 39 is a right-rear perspective view thereof;
FIG. 40 is a front elevational view thereof;
FIG. 41 is a top plan view thereof;
FIG. 42 is a rear elevational view thereof;
FIG. 43 is a bottom plan view thereof;
FIG. 44 is a right-side elevational view thereof; and,
FIG. 45 is a left-side elevational view thereof.
In FIG. 9, the strap, which forms no part of the claimed design, is removed so that it does not obscure the design. In the drawings, the broken lines are for the purpose of illustrating portions of the combined headset with mask and form no part of the claimed design.
